Primary Examiner — Philip S Hyder*Assistant Examiner* — Cary M Robinson(74) *Attorney, Agent, or Firm* — Marshall, Gerstein & Borun LLP(57) **CLAIM**

The ornamental design for a display panel with animated graphical user interface, as shown and described.

DESCRIPTION

FIG. 1 is a front view of a display panel with animated graphical user interface of the present invention, the figure showing a first image in a sequence of images of an animated graphical user interface;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The outermost circle in broken lines in each of the drawings illustrates the display panel. The broken lines in each of the figures illustrating the display panel, and the broken lines illustrating the alphanumeric characters, symbols and icons that are portions of the graphical user interface do not form part of the claimed invention.

The process or period in which one image transitions to another forms no part of the claimed design.
